UNITED STATES PATENT OFFICE.

PAUL K. HEISLER, OF ST. MARYS, KANSAS.

DESIGN FOR A BOB-SLED.

47,593.

Specification for Design.

Patented July 20, 1915.

Application filed September 28, 1914. Serial No. 863,992. Term of patent 14 years.

To all whom it may concern:

Be it known that I, PAUL K. HEISLER, a citizen of the United States, residing at St. Marys, in the county of Pottawatomie and State of Kansas, have invented a new, original, and ornamental Design for a Bob-Sled, of which the following is a specification, reference being had to the accompanying drawing, forming part thereof.

The figure is a perspective view of a bobsled, showing my new design.

I claim:

The ornamental design for a bobsled, as shown.

PAUL K. HEISLER.

Witnesses:

JOSIE A. DE MARAIS,
THOMAS J. MOSS.
